F. BASEL

CONVERTIBLE VALLEY AND HIP COMPOSITION SHINGLE

Filed June 14, 1922

INVENTOR.
FRANK BASEL.
BY HIS ATTORNEY.

James F. Williamson

UNITED STATES PATENT OFFICE.

FRANK BASEL, OF MINNEAPOLIS, MINNESOTA, ASSIGNOR OF ONE-HALF TO PATRICK HALLORAN, OF MINNEAPOLIS, MINNESOTA.

CONVERTIBLE VALLEY AND HIP COMPOSITION SHINGLE.

Application filed June 14, 1922. Serial No. 568,168.

To all whom it may concern:

Be it known that I, FRANK BASEL, a citizen of the United States, residing at Minneapolis, in the county of Hennepin and 5 State of Minnesota, have invented certain new and useful Improvements in Convertible Valley and Hip Composition Shingles; and I do hereby declare the following to be a full, clear, and exact description 10 of the invention, such as will enable others skilled in the art to which it appertains to make and use the same.

This invention relates to a roof shingle especially adapted to be used in the valley 15 of a roof or along the hip of the roof. While the shingle can be made of various materials it is preferably made of a material now commonly used in artificial shingles which comprises various compositions of tar 20 and asphalt, and the like.

It has heretofore been the common practice to place a bent metal strip along the valley of the roof forming a roof gutter or to place a similar strip along the hip 25 of the roof. This practice not only required a special construction at the valley or hip but also marred the uniform appearance of the roofing material.

It is an object of this invention, therefore, to provide a shingle which can be used in overlapping relation in the valley or along the hip of a roof in combination with and as a continuation of the regular standard 30 shingles.

It is a further object of the invention to provide such an artificial shingle having its top and bottom edges diverging downwardly or rearwardly from the shingle center line and having the side edges thereof 40 extending perpendicularly to its top and bottom edges.

These and other objects and advantages of the invention will fully appear from the following description made in connection 45 with the accompanying drawings in which like reference characters refer to the same parts throughout the different views, and in which,

Fig. 1 is a plan view of the roof valley 50 showing the shingles thereon;

Fig. 2 is a similar view of the hip portion of the roof;

Fig. 3 is a plan view of the shingle of the present invention;

Fig. 4 is a view as seen from the bottom 55 of Fig. 3; and

Figs. 5 and 6 are diagrammatic views showing the method of forming the shingle. Referring to the drawings, especially Fig. 1, a valley of a roof having sides A and B 60 is illustrated, the said sides having laid thereon courses of artificial shingles 1. These shingles are illustrated as the standard four-in-one type having the dividing grooves 2 extending partially therethrough from the 65 bottom edges.

The shingle of the present invention is shown as 3 in Figs. 3 and 4 and comprises two side portions adapted to be bent along the longitudinal center line 4. The side portions of the shingle will be bent to lie flat against the sides of the roof valley and the side edges 5 of the shingle extend normal to the top and bottom edges thereof and are adapted to contact and abut against the 70 edges of the standard shingles 1. The respective shingles 3 will be overlapped the same distance as the shingles 1 so that the structure of the roof will be continuous and 75 uniform in appearance across the valley of 80 the roof.

If the shingle 3 is used on the hip of the roof the same is merely reversed in position, the long edges thereof becoming the bottom edges. The side edges 5 abut in 85 the same manner against the artificial shingles shown as 6 in Fig. 2, the shingle 3 being overlapped in the same manner as already described. It will thus be seen that a uniform structure and appearance of the 90 roof is continued across the hip of the roof. With the described structure it is unnecessary to provide a metal gutter extending longitudinally of the roof valley or of a metal strip extending longitudinally of the 95 hip of the roof.

It will be apparent that the angle of the top and bottom sides of the shingle with the longitudinal center line will vary with roofs of different pitches. The said angles 100 are determined in the following manner.

Referring to Figs. 5 and 6, and assuming a roof of $\frac{1}{3}$ pitch or 8 units rise in 12 units of width, the triangle c will be marked out by means of a square or other instruments 105 having a base of 12 units length and its altitude of 8 units length. The hypotenuse of this triangle will then be approximately

14 $\frac{7}{8}$ units. The triangle D is then laid out having its base of 14 $\frac{7}{8}$ units in length and its altitude of 12 units in length. The strip of material 7 of a desired width is then 5 laid with one of its parallel sides extending along the hypotenuse of the triangle D and the side of 12 units in length is continued across said strip at the line b until it intersects the line e—e which is the center 10 line of strip 7. Another line f is then drawn parallel to the line b at the desired distance and this forms the bottom line of the shingle. If the sides of the roof valley are of the same pitch the other side of the 15 shingle will be formed by drawing lines g from the intersection of the lines f and b with the line c—e, making the same angle with the line e—e. If the pitch of the other 20 side of the roof valley is different, the other side of the shingle will be shaped in the manner described, by laying out the proper triangles. The shingles are then cut from the strip 7 and the sides 5 cut to extend 25 perpendicular to the top and bottom edges thereof. It will, of course, be apparent that a pattern of the shingle could be first made and the shingle thereafter cut from a sheet with the proper die. With shingles so constructed the top and bottom edges will, when 30 the shingle is in position, extend parallel to the top and bottom edges of the standard shingles 1.

From the above description it is seen that

applicant has provided a device having great utility and one that can be easily and inexpensively made and that will materially reduce the cost of roof construction. The roof formed at the same time, will be more uniform in appearance than if the old construction of roof gutter or hip plate were 35 used.

It will, of course, be understood that various changes may be made in the form and proportions of the device and in the method of making the same without departing from 40 the scope of applicant's invention, which, generally stated, consists in the matter shown and described and set forth in the appended claim.

What is claimed is:

50 A composition shingle for the roof hip or valley comprising a sheet of flexible material having top and bottom edges diverging from a longitudinal center line along which line the sheet is bent, the side edges 55 of said sheet being perpendicular to its top and bottom edges whereby the sheet can be bent about its center line to various angles and the top and bottom edges thereof can always lie in horizontal planes so that 60 the shingle can be used for roofs of slightly varying pitches and for hips and valleys of different angles.

In testimony whereof I affix my signature.

FRANK BASEL.
